W. E. FRANKLIN

POLE SETTER

Filed Oct. 6, 1924

Inventor
William E. Franklin
by Bair & Freeman Attorneys

UNITED STATES PATENT OFFICE.

WILLIAM E. FRANKLIN, OF EARLHAM, IOWA.

POLE SETTER.

Application filed October 6, 1924. Serial No. 741,965.

To all whom it may concern:

Be it known that I, WILLIAM E. FRANKLIN, a citizen of the United States, residing at Earlham, in the county of Madison and 5 State of Iowa, have invented a certain new and useful Pole Setter, of which the following is a specification.

The object of my invention is to provide a pole setter of simple, durable and comparatively inexpensive construction adapted to 10 be folded into a comparatively small amount of space so that it can be carried conveniently upon a light automobile truck.

In this connection, it may be mentioned 15 that it is quite desirable to have a device whereby the setting of telephone poles in rural communities may be easily and quickly completed where only one man is available to do the work, as is the case in rural 20 communities where the telephone lines are kept in order by a single "trouble man" over a certain amount of territory.

It is, therefore, my object to provide a device which can be collapsed or folded and 25 which can be positioned so that a telephone pole can be placed in the ground without overtaxing the strength of the worker or "trouble man".

With these and other objects in view, my 30 invention consists in the construction, arrangement and combination of the various parts of my device, whereby the objects contemplated are attained, as hereinafter more fully set forth, pointed out in my claim, and 35 illustrated in the accompanying drawings, in which:

Figure 1 is a perspective view of my improved pole setter with a pole shown in partly elevated position.

Figure 2 is a plan view of the pole setter in collapsed position.

Figure 3 is a detail, sectional view taken on line 3—3 of Figure 2 showing a windlass structure.

Figure 4 is a detail, sectional view taken on line 4—4 of Figure 2, showing the means whereby the legs of the setter are connected together; and

Figure 5 is a sectional view taken on line 5—5 of Figure 2 showing one leg as being adjustable.

In the accompanying drawings, I have used the reference characters A, B and C to indicate the three legs of the device.

The legs A and B are each connected at

their upper ends with U fittings 10, which receive a pipe or tubular member 11 and are secured thereto by rivets 12.

The rivets 12 permit the legs A and B to pivot therearound so that they can be positioned close together or spaced apart as desired.

The leg C, which is the third leg, has fixed to its upper end a yoke element 13 by means of the rivets 14.

Each of the ends of the yoke 13 are spaced somewhat apart and are formed with U shaped projections 15 so that a pocket may be formed in which is received the member 11.

The fingers of the U 15 are connected together by a rivet or bolt 16 which is positioned above the member 11, as clearly shown in Figure 4 of the drawing.

The member 11 has fixed to it an eye bolt 17 which is connected to eye bolts 18 on the legs A and B by chains 19. The chains 19 limit the amount of outward pivotal movement of the legs.

From the construction of the parts just described, it will be seen that the legs A and B can be swung on their pivots 12 and that the leg C can be swung upon the member 11 at its pivot.

The leg B has a stub leg 20 secured thereto by two fittings 21 and 23. One fitting is secured to the leg B and the other to the leg 20. The fittings are slideable relative to the leg B or 20 so that they may be clamped thereto, thus permitting adjustment of the leg 20 relative to the leg B.

In order to lock the fitting 21 relative to the leg B and to lock the fitting 23 relative to the leg 20, I provide a thumb screw 24 in each of the fittings 21 and 23.

From the construction of the parts just described, it will be seen that by loosening the two thumb screws 24, I am able to adjust the position of the leg member 20 upon the leg B.

Formed as part of the fitting of the yoke 13, is a pulley 25, which has extended therearound a rope or the like 26. One end of the rope 26 is fastened to a windlass D, which I will now describe in detail.

The windlass D includes a fitting or frame 26 having a longitudinal groove therein which receives the leg C and is secured therearound by rivets or bolts 27 extending through the openings 28.

The fitting or frame D includes two spaced supports 29 in which is a pair of shafts 30 and 31.

A gear 32 is mounted upon the shaft 30, 5 which is in mesh with the gear 33 formed as a part of a drum 34 mounted upon the shaft 31.

The shaft 30 has a handle 35 secured thereto whereby the drum may be operated 10 by rotation thereof.

The rope 26 is fixed to the drum 34.

In order to lock the rotation of the shaft 30 in a backward direction, when it is being operated, I provide a pivoted pawl 36, as 15 clearly shown in Figure 3 of the drawings.

The rope 26 is secured to a telephone pole 37 designed to be set in the ground just beyond its center, as clearly shown in Figure 1 of the drawings.

20 In order to prevent the support or setter from upsetting, I secure a chain or the like 38 to the eye bolt 17, which chain I wrap around the butt or lower end of the pole 37 so that when I rotate the windlass and elevate the pole 37 the chain 38 serves to maintain the three legged device in proper position until the pole is moved to vertical position.

I have used my pole setter in actual prac-

tice and find that it can be successfully operated for setting a telephone pole or other pole in the ground where ordinarily one man cannot accomplish the result desired. 30

Some changes may be made in the construction and arrangement of the various 35 parts of my invention, without departing from the real spirit and purpose of my invention and it is my intention to cover by my claim, any modified forms of structure or use of mechanical equivalents, which may 40 be reasonably included within its scope.

I claim as my invention:

A pole setter comprising a device having three legs secured at their upper end to a common member and each being capable of pivotal movement relative to the common member, a windlass on one of said legs, a pulley positioned near said common member, a flexible element secured to said windlass extending around said pulley and 45 adapted to have its free end secured to the pole to be set and a second flexible element secured to the three legged device for anchoring to the butt end of the pole to be set for maintaining the three legged member in 50 upright position.

Des Moines, Iowa, Oct. 3, 1924.

WILLIAM E. FRANKLIN.
